WRENCH

Walter C. Biles, Bremerton, Wash.

Application December 10, 1943, Serial No. 513,679

2 Claims. (Cl. 81—51.3)

This invention relates to improvements in wrenches and has reference more particularly to wrenches of a special design, or form that adapts them to a specific use; namely, that of tightening the packing nuts in what are known as marine stuffing tubes, where the tubes are closely arranged. It is to be understood, however, that the wrench is well adapted to various other uses and is not to be limited to that above mentioned.

In order to impart a better understanding of the objects of the present invention and its need, it will here be explained that, in ship construction, and especially in the electrical installations of war ships, there are innumerable banks or panels of stuffing tubes through which circuit conduits or cables are passed. It is common to have a plurality of rows of such tubes, of various size, closely arranged at a place where they pass through a plate or bulkhead, and each tube is fitted at its end with a packing nut through which the cable extends. Due to the particular arrangement of tubes and the cables leading thereto, it is exceedingly difficult, with the ordinary types of wrenches, to reach the packing nuts, let alone turning them. Furthermore, it frequently is the case that some of the tubes are shorter, or extend beyond the others, thus adding to the difficulty in reaching the nuts which are applied to those which are shorter, or to turn a nut even though the jaws of the wrench may be applied thereto.

Due to these above conditions, much time is lost and much annoyance results from the attempted use of ordinary types of wrenches, and even special wrenches for this purpose have not been used with any particular degree of satisfaction due to the closeness of cables leading to the tubes and irregularity in lengths and sizes of tubes or due to their being located in close corners or set down within housings that prevent application or use of any ordinary wrench.

In view of the foregoing, it has been an object of this invention to provide a wrench of special design that is adapted for an easier application between the cables extending from closely arranged tubes, and which can be functionally applied to a packing nut regardless of the fact that the cable enters the tube through the nut.

It is also an object of the invention to provide a wrench that can readily and easily be adjusted to fit nuts of a wide range of sizes.

Still another object resides in the provision of a wrench comprising a pair of pivotally joined jaws, wherein a pivot bolt, providing connection between the jaws, is fixed in one jaw and may

be applied to pivot openings in the other at various positions, as a means of determining the working angle of the jaw handles with respect to the gripping plane of the jaws.

More specifically stated, the objects of the invention reside in the provision of a wrench wherein the jaws are offset laterally from the opening and closing plane of the jaw handles, and also lie in a plane that is at a right angle thereto, and wherein the jaws have a special shape that adapts them to be applied to nuts in close quarters and permits them to be turned without interference by closely arranged tubes and cables.

Other objects of the invention reside in the specific shape of parts and in their relationship, their combination and mode of use, as will hereinafter be fully described.

In accomplishing these and other objects of the invention, I have provided the improved details of construction, the preferred forms of which are illustrated in the accompanying drawings, wherein:

Fig. 1 is a perspective view showing a bank or pad of tubes, and illustrating the operation of a wrench, embodied by the present invention, to a nut.

Fig. 2 is a side view of a wrench of the present invention in its most common construction.

Fig. 3 is an under side view of the same.

Fig. 4 is an end view of the wrench, particularly showing the lateral offsetting of the jaws from the plane of the jaw handles.

Fig. 5 is a perspective view of a wrench of a modified or alternative form of design.

Fig. 6 is an enlarged sectional view showing the pivot bolt details, whereby the jaw handles are held functionally together.

Fig. 7 is a view illustrating another adjustment of the wrench.

Referring more in detail to the drawings:

First describing the wrench illustrated in Figs. 2, 3 and 4: This wrench comprises the two handles, or lever arms, 1 and 2, each of which is in the form of a straight, flattened bar, of substantial length and formed at its outer end with a rounded hand hold or gripping portion 3. At their inner ends, the lever arms are formed with the nut gripping jaw portions which later will be described in detail.

One of the lever arms, here designated by numeral 1, is formed at its inner end with an enlarged head portion 4, and this lies in the same plane as the main shank of the lever, but depends therefrom substantially below the lever, as it is shown in Fig. 2, thus forming a flat body portion

of substantial width and depth, and at the forward lower edge of this is formed the inner nut gripping jaw 5. The flat head portion 4 lies flatly against a flat side of the shank portion of lever 2, with the latter extended beyond the head 4 and there formed with a nut gripping jaw 6 that is in opposed relationship to the jaw on lever 1.

Extending through the depending head portion 4 and lever 2 is a pivot bolt 7 whereby the lever arms are pivotally joined. This bolt, fixed on lever 1, extends to one side of the lever and has a portion thereof that is adapted to be selectively applied to any one of a plurality of holes 8 that are formed through the lever arm 2 along its length between the gripping portion 3 and the jaw portion.

The pivot bolt 7, as illustrated best in Fig. 6, has a squared portion 10 intermediate its ends, that fits in a similarly shaped hole 11 in the head portion of the lever 1 to keep the bolt from turning therein. Adjacent this squared portion 10, the bolt is formed with a shoulder 12, and beyond the shoulder, the shank of the bolt is threaded as at 13. This threaded end portion of the shank is applied through the hole 11 and beyond the face of lever 1, and is then secured by a nut 14 threaded thereonto that draws the shoulder 12 down tightly against the face of the lever and locks the squared section 10 in the hole 11. The end portion of the pivot bolt that is opposite the threaded end is round, and this part is applicable to any one of the holes 8 in the lever 2 to form the pivotal connection between levers, and there is a key or pin 15 through the outer end portion of this rounded portion of the pivot bolt which retains the bolt from slipping out from the hole to which it has been applied.

In order that the levers may be easily and quickly disconnected when an adjustment of the jaws is to be made for the purpose of adapting the wrench to a larger or smaller nut, each of the holes 8 is formed, at diametrically opposite sides, with keyways 16, and it is possible, by the opening apart of the handles beyond the usual working position, to register the ends of the locking key 15 with the slots or keyways 16 so that the pivot bolt may be unseated from the pivot opening. In ordinary use of the device, the key or pin 15 retains the levers in their assembled, functional relationship. The holes 8 are relatively close together and thus provide for quite an accurate adjustment for any size nut within the range of sizes provided for.

It is to be noted by reference to Fig. 2 that the head portion 4 of the lever 1 is formed with a series of square holes 11' that are formed therein along a line which is at a right angle to the longitudinal direction of the lever. These holes are so arranged that by placing the pivot bolt 7 in the lower one of them, the lever arms, when closed together, and the jaws applied to a nut for turning it, will extend at a right angle to the axis of the nut. By applying the pivot bolt 7 in a hole 11' that is higher up in the row in the head, will locate the jaw 5 somewhat below the jaw 6, and then when the jaws are functionally applied to a nut, it will place the levers in an upwardly directed angle relative to the plane of the nut. This upwardly directed position of the handles is desirable when the jaws have to be applied to a nut that is set down between rows of tubes or closely adjacent a housing wall as it throws them out of the way of the adjacent tubes. The adjustment above referred to is illustrated in Fig. 7, which shows the pivot bolt 7 as applied to the

upper one of the row of squared holes 11'.

The shape of the jaws of the wrench and their relationship to the plane of the lever arms, is an important part of this invention. Referring to Fig. 5, it will be understood that the jaws 5 and 6 extend laterally to one side of the plane of the levers. The jaw 5, which is integral with the head portion 4 of lever 1, has its nut gripping face set slightly forward of the vertical edge of the head, as seen in Fig. 2, and it is laterally offset from the plane of the head portion 4. The gripping surface is of substantial width and height, and lies in a plane that is perpendicular to the longitudinal axis of the lever arm.

The jaw 6, which is formed at the forward end of lever arm 2, curves laterally and downwardly from the forward end of the lever to be directly opposed to the gripping surface of jaw 5 when the parts are in position as shown in Fig. 2. The gripping surfaces are knurled for better holding effect. With the jaws offset from the plane of the levers, their application to a nut will locate the lever arms out of the way of any cable passing through the nut.

It is an important feature of construction also that the nose of the jaw 6 is rounded off as at 35 and 40 in Fig. 3, and that the nose of jaw 5 is rounded off as at 41, to facilitate turning the wrench in close quarters; also that the jaw ends be rounded as at 42 and 43 for working in close quarters.

In Fig. 5, I have shown a wrench of an alternative design, but for the same uses as that wrench already described. The jaws and mode of connecting the levers is the same, but the lever arms are turned upwardly to a line that is substantially parallel to the axis of the nut to which the wrench jaws are to be applied. This wrench is more especially designed for use where it is required to reach down between tubes to apply a nut.

Wrenches of this kind are being used with great success in the ship building industry and have proven to be more desirable for the particular use herein stated than any wrench previously employed for this purpose. They may be made in various sizes, according to any particular use, and the shape of jaws altered as required for any special requirement.

Having thus described my invention, what I claim as new therein and desire to secure by Letters Patent is:

1. A wrench of the character described comprising a pair of complementary handle forming levers, a pivot bolt joining end portions of the levers with one extended beyond the other; each lever being formed at its pivoted end with a laterally offset and downwardly directed jaw forming portion for gripping an object between them; one of said levers having a series of holes therein in a line that is transverse to the longitudinal line of the lever and adapted to selectively receive said pivot bolt to change the angle of application of the wrench to an object, and the other of said levers having a succession of holes therealong to receive the pivot bolt to adapt the jaws to grip objects of different size.

2. A wrench of the character described comprising two complementary handle forming levers, a pivot bolt joining the outer end portions of the levers, with the end portion of one extended beyond the end of the other and turned laterally and downwardly and forming a gripping jaw that is disposed at a right angle to the opening and closing plane of the levers and said lever having

a series of holes therealong to receive the pivot bolt, the other lever being formed at its pivoted end with a flattened head portion with a series of holes formed therein in a line at a right angle to the direction of the handle to which the pivot bolt may be selectively applied, and having a jaw forming portion at the lower edge of the

said head portion, extended at a right angle thereto and in opposed relationship to the first mentioned jaw; said jaws having their end portions rounded off for clearance in turning an object, and having their under surfaces rounded upwardly and away from the gripping surfaces.

WALTER C. BILES.
